UNITED STATES PATENT OFFICE.

HERMAN L. HANSON, OF MEDFORD, AND FREDERICK J. JOHNSTON, OF BOSTON, MASSACHUSETTS.

SIPHON-BOTTLE.

SPECIFICATION forming part of Letters Patent No. 292,014, dated February 5, 1884.

Application filed December 5, 1883. (No model.)

To all whom it may concern:

Be it known that we, HERMAN L. HANSON, of Medford, in the county of Middlesex and State of Massachusetts, and FREDERICK J. JOHNSTON, of Boston, in the county of Suffolk and State of Massachusetts, have jointly invented certain new and useful Improvements in Siphon-Bottles, of which the following, taken in connection with the accompanying drawings, is a specification.

Our invention relates to siphon-bottles in which soda-water and other similar beverages under pressure are put up for use; and it consists in certain novel features in the neck thereof and the metallic head attached thereto, which will readily be understood by reference to the description of the drawings, and to the claims to be hereinafter given.

In the drawings, Figure 1 represents a central vertical section of the neck and head of a siphon-bottle of the usual construction. Fig. 2 represents a similar view of our improved siphon-bottle. Fig. 3 represents an inverted sectional plan on line $x-x$ in Fig. 2. Figs. 4 and 5 represent, respectively, a side elevation and an inverted plan of one-half of a modified form of the coupling-ring. Fig. 6 represents a side elevation of the neck and coupling-ring of a modified form of our improved siphon-bottle. Fig. 7 represents a central vertical section of same on line $y-y$ on Fig. 6, and Fig. 8 represents an inverted sectional plan of the same on line $z-z$ on Fig. 7.

In order to prevent the escape of the carbonic-acid gas from the beverage contained in the bottle, it is necessary that the head B should be firmly secured to the neck of the bottle, so as to make a perfectly air-tight joint, as any escape of the gas contained therein renders the contents of less value, and, if the gas should continue to escape the beverage would soon become entirely worthless. Heretofore this object has been sought to be accomplished by the device shown in Fig. 1, in which A is a soda-water bottle of the usual construction, the neck of which is provided with a suitable flange, a , the lower edge of which forms a shoulder, against which the upper edge of the divided coupling-ring $b-b$ abuts when the head

is screwed thereto. The upper part of the divided or two-part ring $b-b$ is provided with a suitable male thread, which enters a cavity in the lower end of the metallic head B, and engages with a suitable female thread formed therein, whereby the shoulder c of the said head B may be firmly pressed down upon the washer d , of rubber or other suitable material, and thus insure an air-tight joint. The usual construction of the metallic head B is as shown in Fig. 1, of which C is the nozzle, D is the valve, and E is the thumb-lever. The head B is firmly secured to the bottle A at the bottler's establishment, after which the bottle is placed in the filling-machine, and the bottle is charged with the required beverage, when it is ready to be delivered to the consumer.

In order to secure the head B to the bottle A, a wrench or clamp has to be used, which is adapted to embrace the flange b' of the divided coupling-ring $b-b$, and hold it while the head B is being turned thereon.

It often happens that because the head is not screwed down sufficiently tight, or on account of the packing losing its elasticity by standing for a long time, these bottles leak while in the consumer's possession, with the result that as he is usually without any suitable appliances to hold the divided ring $b-b$ while he screws down the head, the carbonic-acid gas continues to escape and the beverage is spoiled, while if it were possible to readily tighten or screw down said head as soon as the leak was discovered, but a small amount of gas would escape and the beverage would be but slightly affected.

To allow for future tightening, the bottom of the head B does not extend as far as the flange b' of the coupling-ring $b-b$, leaving a space, which is apt, in cleaning the metallic head B with whiting or any similar substance, to get filled with said substance and present an untidy and dirty appearance. To obviate these objections is the object of our present invention, to accomplish which we have constructed the device shown in Figs. 2 and 3.

The neck of the bottle A is provided with two lugs, ee , molded or otherwise formed thereon, one opposite to the other, each of which projects outwardly into a suitable notch or re-

cess, *f*, of one of the halves of the coupling-ring *b b*. The notches *f f* may extend through the entire thickness of the coupling-ring *b b*, as shown in Figs. 4 and 5, if desired; but a recess such as is shown in Figs. 2 and 3 is much more preferable, as a much neater appearance is thereby obtained. By means of these lugs *e e* fitting into the notches *f f* of the coupling-ring *b b* it is obvious that the head *B* may be readily turned thereon, so as to clamp the washer firmly against the top of the bottle and insure a tight fit without the use of any implement to hold the coupling-ring in fastening. The neck of the bottle may be provided with two lugs, *e e*, on either side thereof, and each half of the coupling-ring *b b* may have formed thereon a downwardly-extending arm or lug, *g*, adapted to fit between said lugs *e e* on the neck of the bottle, as shown in Figs. 6, 7, and 8, and thereby prevent the said ring *b b* from turning when the head *B* is being screwed thereon. This construction will accomplish the same purpose as that which has already been described, and may be used without in any wise affecting the principles of our invention.

In order that the metallic portions of the siphon-bottle may at all times present a neat appearance and offer no spaces or grooves in which dirt of whiting might collect, the coupling-ring *b b* is provided with an annular lip, *b'*, which extends upwardly about the lower part of the head *B*, which is made slightly tapering to fit the corresponding tapering inner edge of the annular lip *b'*, as shown in Fig. 2, so that when the head *B* is screwed down upon the washer *d* the two tapering surfaces come together and form a substantially tight joint, thus doing away with any spaces or grooves which might become filled with whiting and present an untidy appearance, while at the same time, owing to the slight taper of the contiguous parts and the nature of the soft white metal usually used for this purpose, the head may be screwed down to tighten the pack-

ing, the contiguous parts expanding sufficiently for the purpose. If one of the lugs *e* should by chance be broken off, the remaining lug would accomplish the purpose of preventing the coupling-ring from being turned upon the bottle. Therefore, if at any time it is desirable to manufacture the siphon-bottles with only one lug, the thing could be accomplished without altering the principles of our invention.

What we claim as new, and desire to secure by Letters Patent of the United States, is—

1. The combination, with a glass bottle having two or more rectangular lugs or ears molded upon and projecting from its neck, and provided with an annular flange or collar at its top end, of a threaded metallic coupling-ring made in two parts and provided with a radial shoulder or shoulders to engage with said lugs or ears, and a head or cap provided with a female thread to engage with the thread on said divided coupling-ring, substantially as and for the purposes described.

2. In a siphon-bottle, the combination of the head *B*, the coupling-ring *b b*, each half of which is provided with a recess or notch, *f*, and the lugs *e e*, molded upon and projecting from the neck of the bottle *A*, substantially as and for the purposes described.

3. In a siphon-bottle, a divided coupling-ring provided with a means of securing thereto to the metallic head of said bottle, and also provided with an upwardly-extending annular lip adapted to inclose the lower end of said head, substantially as and for the purposes described.

In testimony whereof we have signed our names to this specification, in the presence of two subscribing witnesses, on this 3d day of December, A. D. 1883.

HERMAN L. HANSON.
FREDERICK J. JOHNSTON.
